UNITED STATES PATENT OFFICE.

JOSEPH ENGEL, OF NEW YORK, N. Y.

DESIGN FOR A RING.

Application filed February 26, 1925. Serial No. 12,493. Term of patent 7 years.

To all whom it may concern:

Be it known that I, JOSEPH ENGEL, a citizen of the United States, residing at New York, in the county of Bronx and State of New York, have invented a new, original, and ornamental Design for a Ring, as shown in the accompanying drawing and described in the following specification.

The figure of the drawing is a side perspective view of a ring constituting my new design.

I claim:

The ornamental design for a ring as shown.

JOSEPH ENGEL.
